UNITED STATES PATENT OFFICE.

HERMAN V. WILLMAN, OF MAYWOOD, ILLINOIS.

DESIGN FOR A LIGHTING-FIXTURE-BOWL SUPPORT.

57,755.

Specification for Design.

Patented Apr. 26, 1921.

Application filed September 2, 1920. Serial No. 407,814. Term of patent 7 years.

To all whom it may concern:

Be it known that I, HERMAN V. WILLMAN, a citizen of the United States, residing at Maywood, in the county of Cook and State of Illinois, have invented a new, original, and ornamental Design for a Lighting-Fixture-Bowl Support, of which the following is a specification, reference being had to the accompanying drawings, forming part thereof.

In the drawings, Figure 1 is an elevation of a lighting fixture bowl support, showing my new design.

Fig. 2 is a plan view of the same.

I claim:

The ornamental design for a lighting fixture bowl support, as shown.

HERMAN V. WILLMAN.
